LIQUID DISTRIBUTOR

George E. Stewart and Carl L. Trier, Baltimore,
Md., and Harold S. Fielder, La Grange, Ill., as-
signors to Cherry-Burrell Corporation, Wil-
mington, Del., a corporation

Application March 29, 1940, Serial No. 326,598

16 Claims. (Cl. 299—58)

This invention relates to new and useful improvements in liquid distributors. More particularly this invention relates to the easily removable and sanitary end caps or closures for distributor pipes used in the distribution of a film of liquid onto the heat exchange surface of a heat exchanger and to the removable and easily disassembled and assembled juncture elements between the distributor pipes and coupling units.

In the sanitary processing of foodstuffs, such as milk, particularly in the heating or cooling thereof as carried on in many commercial adaptations of heat exchangers, the milk is distributed in a thin film onto the heat exchange surface of a heater or cooler. Such heaters or coolers usually comprise a comparatively thin but relatively wide, hollow heat exchange surface with the heating or cooling medium flowing through passages on the inside of the heat exchanger while the product to be heated or cooled flows over the outer surface of the element in a thin film.

A very common means for supplying the film of liquid to be heated or cooled to the heat exchange element is a distributor pipe. Such a distributor pipe consists primarily of a suitable length of sanitary piping provided with a straight row of nozzles or apertures alined with and positioned directly above the upper edge of the heat exchange element. These nozzles or apertures are so arranged and positioned that they are adapted to direct a multiplicity of closely adjacent jets of liquid onto the top of the surfaces of the heat exchange element. These jets of liquid, upon contacting the surfaces of the heat exchange element, spread out and join to form a film of liquid over the entire surface of the heat exchange element.

The construction of the heat exchange element, the distribution pipe and associated closures therefor, and junction elements must, when used for handling foodstuffs and particularly those of a perishable nature, be of a sanitary design. The conventional distributor pipes, closure elements and coupling elements have not been particularly satisfactory from a sanitary standpoint. From a mechanical standpoint the distributor mechanism assemblage has not been entirely satisfactory in that it has not lent itself readily to easy assembly and disassembly. Normally the closure and coupling elements include structural features having threaded or creviced portions exposed to the milk surface and positioned where they are not readily accessible for inspection and cleaning.

The prime object of this invention is to provide a sanitary, easily removable and easily assembled closure cap and coupling or juncture element for a distributor pipe including the necessary means to secure the alinement of the spray nozzles or apertures of the distributor pipe with the associated edge of the heat exchange element and to avoid the use of internally exposed screw threads, crevices or flanges on the surfaces thereof which are not exposed for inspection and readily accessible for cleaning.

A further object of the present invention is to provide a readily removable, sanitary distributor pipe closure and coupling element, as referred to above, which is quickly and easily assembled, which is quickly and easily mounted in position upon the heat exchanger; and in which the closure and coupling elements are maintained in sealed relation while in operative position without the use of threaded coupling nuts, etc., whereby exposed threads, shoulders or flanges and the like are positioned on the inside of the distributor pipe where they are not readily accessible for cleaning and inspection.

One of the important features of the present invention is the production of a sanitary, easily assembled and removable closure for the end of a distributor pipe which co-acts with the complementary portions of the heat exchange section upon which it is supported to provide a distributor pipe, together with closure elements therefor, which is easily assembled upon the heat exchanger and which is maintained in proper predetermined alinement and operative position.

The foregoing objects and other important features which it is desired to accomplish will become apparent as the nature of the invention is better understood. The organization of the elements of the invention is well set forth in the following description of the invention when read in connection with the accompanying drawings in which:

Figure 1 is a side elevational view of a heat exchanger partially in broken-away section provided with an improved distributor pipe and closures therefor shown in longitudinal sectional elevation.

Figure 2 is a plan view of the cooler and distributor mechanism shown in Figure 1.

Figure 3 is a transverse sectional elevational view taken at the end of the distributor pipe showing in end elevation the assembled closure cap and compression spring assemblage.

Figure 4 is a perspective view of a compression

spring whereby the closure cap on the end of the distributor pipe is sealed thereto.

Figure 5 is a side elevational view partially in broken-away section of a modified construction of the distributor pipe and end closures therefor and the upper portion of the heat exchanger upon which the distributor mechanism rests.

Figure 6 illustrates the various elements of the modified end closure shown in Figure 5 in their relative order of assembly.

Referring to the figures showing the preferred embodiments of the invention, like numerals being used to identify like elements, 10 represents the opposed vertical headers of a heat exchanger having projecting tubular bosses 11 sealed to and supporting horizontally disposed transversely extending tubular elements 12 which comprise the heat exchange surface. The headers 10 are provided with internal partitions 13 to cause the heat exchange medium which enters one header through the conduit 14 to flow a zigzag passage through the inter-connecting pipes or tubular elements 12 and be subsequently discharged from the opposite header through discharge pipe 15.

A collecting trough 16 is provided below the heat exchange element and is removably supported thereon by an interlocking arrangement of lugs upon the lower ends of the opposed headers 10 and the outer ends of the collecting trough 16. The collecting trough 16 is adapted to collect the milk or other liquid which is passed over the outer surface of the heat exchanger.

The liquid to be processed is supplied through supply pipe 17 to a sectional distributor pipe 18 removably connected to the supply pipe 17 by a connecting or coupling T 19. The essential distributor pipe 18 and the coupling T 19 are provided along their lower wall with distributing nozzles or apertures 20 alined with the top edge of the uppermost transverse conduit 12 of the heat exchange element. Liquid to be heated or cooled enters through pipe 17 and connecting or coupling T 19 into the sections of the distributor pipe 18 from which it is distributed in a multitude of small streams onto the upper surface of the topmost heat exchange pipe 12. The apertures 20 are positioned very close together and the small streams of liquid exuding therefrom, when impinged against the surface of the heat exchange pipe 12, tend to spread out and unite, forming thereby a film which flows down over the series of heat exchange pipes 12 into the collecting trough 16.

The sectional distributor pipe 18 and coupling T 19 are removably supported upon the top of the opposed headers 10 upon which they rest. The apertures 20 are maintained in vertical alinement with the top of the uppermost heat exchange pipe 12 by the interlocking engagement of vertically disposed flat lugs 21 on the outermost ends of the closure caps 29 for the outer ends of the distributor pipe 18 with the walls of the vertical grooves 22 in the upwardly extending heat exchanger support means or brackets 23 fixed to or formed integrally with the upper ends of the headers 10. The construction as just described provides a splined connection between the distributor pipes 18 and the closure cap 29 and between the closure cap 29 and the brackets 23. The spline connection is formed by the slots 31 in the caps 29, the edges of which slots engage the studs 26 in a collar 24 on the ends of the pipe 18.

The preferred embodiment of the present invention, as illustrated, comprises a heat exchanger intended preferably for liquid dairy prod-

ucts, such as milk. Obviously the sanitary features of such apparatus used in the processing of milk or other perishable foodstuffs are of ultimate importance.

5 In the daily use of heat exchangers of the type illustrated, it is essential that all the surfaces, interior as well as exterior, which come into contact with the milk be thoroughly and frequently cleaned. Accordingly, it is necessary that the 10 sectional distributor pipe and coupling elements, and the end closures for the distributor pipe be readily assembled and disassembled upon the heat exchanger and that all these elements be of a sanitary design. It is further of ultimate importance that, when the various elements referred to above are disassembled, all portions thereof be readily accessible for inspection and cleaning. It is also essential that the various elements referred to above be quickly and readily assembled into operative position upon the heat exchanger and, when assembled, be satisfactorily sealed and alined in operative position. To accomplish these various desirable objectives in a simple, efficient and inexpensive manner is one of the prime purposes of this invention.

The maintenance of the sealed relation between the various sections of the sectional distributor pipe 18, the coupling element 19 and the sealing of the outer ends of the pipe 18 and the maintenance of the assembled mechanism in proper operative position have been accomplished by the provision of non-rotatable compressed end closures and coupling elements. The outer and inner ends of the distributor pipe 18 are provided 30 with collars 24 having beveled end faces 25 and outwardly projecting studs 26 on the outer periphery of the collars 24 or pipe 18. The inner ends of the pipes 18 with their outer peripheral collars 24 are telescoped into the bores in the ends of the connecting T 19 which are provided with beveled inner shoulders 27 complementary to the beveled inner faces 25 of the collars 24.

To prevent the relative rotation between the connecting T 19 and the pipes 18 the ends of 45 the connecting T 19 are provided with slots 28 to engage the studs 26 on the outer periphery of the collars 24 or the pipes 18, thereby providing a splined connection between the distributor pipes 18 and the connecting T 19. In this manner 50 alinement of the apertures 20 in the bottom of the pipes 18 and the connecting T 19 is secured and maintained.

To seal the outer ends of the pipes 18 closure caps 29 are telescopically fitted over the collars 55 24 on the ends of the pipes 18. The closure caps 29 are provided with inner beveled shoulders 30 complementary to the beveled ends 25 of the collars 24. To prevent relative rotation between the closure caps 29 and the pipes 18 the caps 29 are 60 provided with slots 31 in the edges of the skirts thereof to engage the studs 26 on the outer periphery of the collars 24.

The caps or end closures 29 of the pipes 18 are 65 provided with transverse vertically disposed lugs 21 which extend into the slots or grooves 22 of the heat exchanger supports or bracket members 23 thereby preventing any relative rotation of the caps 29 with respect to the brackets 23. This construction of lugs fitted into complementary grooves in the supporting brackets 23 enables the easy assembly and disassembly of the distributor mechanism upon the heat exchanger by merely moving the assembled distributor mechanism vertically into or out of operative position with the lugs 21 registering with the grooves 70 75

22 in the brackets 23. By the above described co-operative relation between the elements 21 and 22 and the studs 26 and slots 28, alinement of the apertures 20 in the distributor pipes 18 and coupling element 19 with the top of the uppermost heat exchange conduit 12 is readily and satisfactorily maintained.

To seal the closure caps 29 to the outer ends of the pipes 18 and to seal the inner ends of the pipes 18 to the coupling element 19 without the use of conventional compression nuts, etc., which normally involve the utilization of unsanitary screw threads which are not readily accessible for cleaning, a compression spring generally indicated by the numeral 32 is provided. The compression spring 32 is interposed between the bracket element 23 at one end of the distributor mechanism and the adjacent end face of the closure cap 29. By such interposition of the compression spring 32 it is compressed and the entire distributor assemblage consisting of sectional distributor pipes 18, coupling T 19 and closure caps 29 is urged toward the opposite heat exchanger bracket element 23, thereby urging the complementary beveled faces 25 and 27 and 25 and 30 into sealing engagement one with another to completely seal the distributor assemblage save for the distributor apertures or nozzles 20.

The compression spring 32, as shown in Figures 3 and 4, is comprised of an upper portion 33 disposed at substantially a right angle to the bowed bifurcated lower portion 34. To assemble the spring upon the distributor mechanism and heat exchanger the bifurcated lower portion 34 is superimposed over the vertical lug 21 of the closure cap 29 with one leg of the bifurcated portion 34 on each side of the lug 21 and with the upper and lower extremities of the bifurcated portion 34 abutting against the bracket element 23 and the bowed section of the bifurcated portion 34 abutting against the adjacent face of the closure cap 29.

The upper portion 33 of the spring 32, when it is in assembled operative position upon the heat exchanger, overlaps the upper extremity of the bracket element 23, as clearly shown in Figure 1. By this arrangement it is only necessary, when desiring to disassemble the distributor mechanism from the heat exchanger, to withdraw the compressed spring 32 and lift the assembled distributor mechanism upwardly until the lugs 21 are clear of the grooves 22 in the bracket element 23.

In Figures 5 and 6 are shown a modified construction of the preferred embodiment of the present invention. In this modified construction the compression spring 32 has been eliminated. To eliminate the compression spring 32 and seal the closure caps 29 against the outer end of the distributor pipes 18, each of the collars 24 has been provided at its rear edge with an outwardly extending threaded flange 35. The threaded flange 35 is adapted to engage an internally threaded coupling nut or sleeve 36 having an inwardly extending flange 37 to overlap and engage the outer face of the closure cap 29. Upon the tightening of the coupling nut or sleeve 36 upon the threaded flange 35, the overlapping and inwardly extending flange 37 will be brought into engagement with the closure cap 29 thereby compressing it against the ends of the pipe 18 to sealingly engage the same.

In both modifications of the invention, as shown in the figures, the arrangement of studs and lugs to maintain the distributor mechanism and the spray apertures therein in alinement

with the heat exchange element of the heat exchanger is the same, as well as the arrangement of the closure caps for the ends of the distributor pipes, end collars on the pipes, and the complementary beveled sealing faces.

Having thus described the illustrated specific and preferred embodiments of the uniquely constructed distributing mechanism for a heat exchanger and having pointed out the unique and 10 novel cooperative relations whereby a distributor mechanism devoid of unsanitary elements has been provided in which the closure elements may be readily assembled and disassembled upon the distributing mechanism and the distributing 15 mechanism readily and quickly assembled upon and disassembled from the heat exchanger, and in which distributing mechanism the closure elements are also used to aline the spray apertures or nozzles of the distributor mechanism with the heat exchange element, the invention is not to be restricted to the specifically illustrated embodiments of the invention disclosed except in so far as necessary by the prior art and the spirit of the appended claims.

25 The invention is hereby claimed as follows:

1. In a liquid distributor, an apertured distributor pipe, means for supporting said pipe, a ferrule at the end of said pipe, a closure cap fitted over said ferrule to close the end of said pipe, co-acting means on said pipe and closure cap to prevent relative rotation between said pipe and said closure cap, and spring means for urging said closure cap against the end of said pipe to close the same.
- 30 2. In combination, a distributor means for liquid having a series of spaced discharge apertures in a wall thereof for discharging liquid in substantially uniform distribution over a portion of the surface of a liquid supporting means, closure caps for the ends of said distributor means, bracket elements extending upwardly from the liquid supporting means, a groove in the inner face of each bracket element, a lug on each of said closure caps to engage the adjacent groove to prevent rotation of said closure caps relative to said bracket element, a slot in the skirt of each of said closure caps, and stud means on said distributor means to engage said slots in said closure caps, whereby the relative rotation of said 40 distributor means, closure caps and bracket elements is prevented.
- 45 3. A liquid distributor comprising, in combination, a bored coupling head, an apertured distributor pipe extending horizontally from and communicating with the bore of said coupling head and having a ferrule at its free end, stud means on said distributor pipe, a closure cap for the ferruled end of said distributor pipe, a slot in said closure cap and in said coupling head for engaging said stud means on said distributor pipe to prevent relative rotation between the same, support bracket means for said distributor pipe, and spring means compressed between said bracket means and said closure cap for urging said closure cap against said distributor pipe and said distributor pipe against said coupling head, whereby said closure cap, distributor pipe and coupling head may be maintained in sealed non-rotatable relation one to another.
- 55 4. A liquid distributor comprising, in combination, a bored coupling head, an apertured distributor pipe extending horizontally from and communicating with the bore of said coupling head and having a ferrule at its free end, stud

means on said distributor pipe, a closure cap for the ferruled end of said distributor pipe, a slot in said closure cap and a slot in said coupling head for engaging said stud means on said distributor pipe to prevent relative rotation between the same, beveled sealing faces at either end of said distributor pipe to engage complementary beveled sealing faces in said closure cap and in said bore of said coupling head, bracket means for supporting said distributor pipe, a vertical groove in said bracket means, a lug on said closure cap to engage the groove in said bracket means, and spring means compressed between said bracket means and said closure cap for urging said closure cap against said distributor pipe and said distributor pipe against said coupling head, whereby said closure cap, said distributor pipe and said coupling head are maintained in sealed relation one to another and maintained in non-rotatable relation with respect to said bracket means.

5. A device of the class described comprising, in combination, a conduit, a closure cap for sealing the end of said conduit, means on said conduit to engage cooperative means on said closure cap to prevent relative rotation between said closure cap and said conduit when said closure cap is in sealing position, means for supporting said conduit and closure cap, and compressed resilient means engaging the supporting means and said closure cap for urging said closure cap into sealing engagement with the end of said conduit.

6. A device of the class described comprising, in combination, a conduit, a closure cap for sealing the end of said conduit, means on said conduit to engage cooperative means on said closure cap to prevent relative rotation between said closure cap and said conduit when said closure cap is in sealing position, means for supporting said conduit and closure cap, compressed resilient means engaging the supporting means and said closure cap for urging said closure cap into sealing engagement with the end of said conduit, and inter-acting tongue and groove means to prevent relative lateral motion between said closure cap and said means for supporting said conduit.

7. A device of the class described comprising, in combination, a fluid distributor, means for supporting said distributor, an opening in said distributor normally adapted to be sealed, a closure for sealing said opening in said distributor, co-acting means on said closure and said distributor to prevent relative rotation between said distributor and said closure, and compressed resilient means for urging said closure against said distributor to seal said opening and to maintain said co-acting means in co-acting engagement.

8. In combination, an open-ended liquid distributor for distributing liquid onto a liquid receiving surface longitudinally thereof, closure means for sealing the open end of said open-ended distributor, and resilient means compressed against said closure means for urging said closure means into sealing engagement with said distributor over the open end thereof.

9. In combination, an open-ended liquid distributor for distributing liquid onto a liquid receiving surface longitudinally thereof, a support for said distributor, closure means for sealing the open end of said open-ended distributor, and resilient means compressed against said support

and engaging said closure means for urging said closure means into sealing engagement with said fluid distributor for sealing the open end thereof.

10. In combination, an open-ended liquid distributor for distributing liquid onto a liquid receiving surface longitudinally thereof, closure means for said open-ended distributor, stationary means for supporting said distributor and closure means, said closure means being splined to said distributor and to said means for supporting said distributor, and means for maintaining said closure means sealed to said distributor, whereby said distributor is prevented from rotating about its axis.

11. In combination, an open-ended liquid distributor for distributing liquid onto a liquid receiving surface longitudinally thereof, closure means for said open-ended distributor, stationary means for supporting said distributor and closure means, said closure means being splined to said open-ended distributor and said means for supporting said distributor by splining means on said stationary means and on said closure means and on said distributor when maintained in sealing position on said distributor, and means for maintaining said closure means sealed to said distributor, whereby said distributor is prevented from rotating about its axis.

12. In combination, a sectional liquid distributor for distributing liquid onto a liquid receiving surface longitudinally thereof, a coupling head for receiving adjacent ends of said sectional distributor, sealing means for the remaining ends of said distributor, and spring means for urging said sealing means into sealing position on said distributor and for urging said adjacent ends of said sectional distributor to said coupling head.

13. In combination, a sectional liquid distributor for distributing liquid onto a liquid receiving surface longitudinally thereof, a coupling head for receiving adjacent ends of said sectional distributor, sealing means for the remaining ends of said distributor, stationary support means for supporting said coupling head, said sectional distributor and said sealing means, and resilient means for urging said sealing means into sealing position on said distributor and for urging said adjacent ends of said sectional distributor to said coupling head, said sealing means and said coupling head being splined to said distributor and said sealing means being splined to said support means, whereby said distributor, said coupling head and said sealing means are prevented from rotating about the axis of said distributor.

14. In combination, a sectional liquid distributor for distributing liquid onto a liquid receiving surface longitudinally thereof, a coupling head for receiving adjacent ends of said sectional distributor, sealing means for the remaining ends of said distributor, a support for said distributor, coupling head and sealing means, and means for urging said sealing means into sealing position on said distributor and for urging said adjacent ends of said sectional distributor to said coupling head, said coupling head and said sealing means being splined to said distributor and said sealing means being splined to said support, whereby relative rotation between said coupling head, said distributor and said sealing means about the axis of said distributor is prevented.

15. In combination, a liquid distributor for distributing liquid onto a liquid receiving surface

longitudinally thereof, a coupling head for receiving an end of said distributor, sealing means for the remaining end of said distributor, a support for said distributor, and means for urging said sealing means into sealing position on said distributor and for urging said distributor to said coupling head, said sealing means and said coupling head being splined to said distributor and said distributor being splined to said support, whereby relative rotation between said coupling head, said distributor and said sealing means about the axis of said distributor is prevented.

16. A device of the type described comprising, in combination, a liquid receiving surface dis-

10 posed between oppositely positioned liquid distributor support means, a liquid distributor having discharge apertures in a wall thereof for discharging and distributing liquid onto said liquid receiving surface and resting upon said support means, closure means for the ends of said distributor, and spring means compressed between said support means and said closure means for urging said closure means against the ends of said distributor for sealing the same.
